Patented Dec. 21, 1920.

FIG. 2

FIG. 3

Inventor
J. H. Reed

By *Watson E. Coleman*
Attorney

UNITED STATES PATENT OFFICE.

JOSEPH H. REED, OF WATERVILLE, MAINE.

BUCKLE.

1,362,738.

Specification of Letters Patent. Patented Dec. 21, 1920.

Application filed February 4, 1920. Serial No. 356,148.

To all whom it may concern:

Be it known that I, JOSEPH H. REED, a citizen of the United States, residing at Waterville, in the county of Kennebec and State of Maine, have invented certain new and useful Improvements in Buckles, of which the following is a specification, reference being had to the accompanying drawings.

10 This invention relates to certain improvements in buckles and has relation more particularly to a device of this general character especially designed and adapted for use in connection with foot wear such as 15 overshoes, and the like, and it is an object of the invention to provide a novel and improved device of this general character comprising two separable members together with means for effectively holding the same 20 against separation when in locking relation. Another object of the invention is to provide a novel and improved buckle of this 25 general character including a tongue carrying member adapted for adjustable and separable connection with a keeper member and wherein the keeper member is provided with means coacting with the tongue for maintaining the members against accidental displacement or separation when in interlocking engagement.

The invention consists in the details of construction and in the combination and arrangement of the several parts of my improved buckle whereby certain important 35 advantages are attained and the device rendered simpler, less expensive and otherwise more convenient and advantageous for use, as will be hereinafter more fully set forth.

The novel features of my invention will 40 hereinafter be definitely claimed.

In order that my invention may be the better understood, I will now proceed to describe the same with reference to the accompanying drawings, wherein:

45 Fig. 1 is a view in plan of a buckle constructed in accordance with an embodiment of my invention.

Fig. 2 is a sectional view taken substantially on the line 2—2 of Fig. 1; and

50 Fig. 3 is a sectional view taken substantially on the line 3—3 of Fig. 1.

As disclosed in the accompanying drawings, the buckle comprises two separable members A and B, each adapted to have an 55 end portion suitably secured to a strap or other flexible member. The member A car-

ries the pivoted or hinged tongue 1 which when in locking engagement with the member B overlies the member A. The portion *a* of the tongue 1 adjacent its pivoted connection with the member A is rounded to afford a raised portion or hump. The tongue 1 is adapted to be inserted through one of the transversely disposed slots 2 produced in the keeper member B and spaced longitudinally thereof. The end portion of the member B remote from its connection with the strap or the like is transversely enlarged to afford the stop shoulders 3.

H denotes a holding member having sliding contact with the longitudinal marginal portions of the member B and which extends transversely across the outer face of said member. Before the members A and B are interlocked or connected by the tongue 1, the member H is moved to a point adjacent to the inner or attached end of the member B. The tongue 1 of the member A is then inserted through the desired slot 2 in the member B and the tongue swung in working position or in a position overlying both the members A and B. It is to be understood that this operation is materially facilitated by the contact of the plate A with the overshoe or other work with which the buckle may be employed.

When it is desired to separate the members A and B, the tongue 1 is slightly raised to effect the requisite depression of the raised portion or hump *a* whereupon the holding member H may be readily moved out of working engagement with said tongue 1.

The free end portion of the tongue 1 is disposed on an outward curvature as at *b* to afford a stop so that when the holding member is in working engagement with the tongue 1, said member is positioned between the portion or hump *a* and the curved portion or stop *b* of said tongue 1.

When the members A and B are separated the holding member H is held against displacement at the outer end of the member B by contact with the stops 3.

It is preferred that the holding member H comprise a substantially rigid metallic strap 4 having its extremities returned, as at 5, for loose engagement with the longitudinal or said marginal portions of the member B whereby said member H is readily held by the member B but capable of sliding movement longitudinally thereof. It is

also preferred that the member H be disposed longitudinally on a slight curvature with the substantially concave face thereof disposed in a direction away from the member B.

From the foregoing description, it is thought to be obvious that a buckle constructed in accordance with my invention is particularly well adapted for use by reason 10 of the convenience and facility with which it may be assembled and operated, and it will also be obvious that my invention is susceptible of some change and modification without departing from the principles and 15 spirit thereof, and for this reason I do not wish to be understood as limiting myself to the precise arrangement and formation of the several parts herein shown in carrying out my invention in practice except as here- 20 inafter claimed.

I claim:

1. A separable fastener comprising, in combination, two members, one of said members being provided with a slot, a tongue 25 pivotally engaged with the other member and adapted for insertion through said slot, said tongue when inserted through the slot of the second member being movable in a position to overlie both of the members, the 30 pivoted end portion of the tongue and the opposite end portion thereof being raised, the portion of the tongue between the opposite raised end portions thereof being arranged longitudinally on a curvature where- 35 by the intermediate portion of said tongue is depressed, and a holding member slidably engaged with the first named member and extending across both of the members when 40 said members are in locking relation, said holding member extending between the raised portions of the tongue, said holding member passing over or from the tongue upon depression of the pivoted end portion 45 of the tongue with respect to the second plate, said second plate being provided with 50 means to prevent the holding member from displacement thereon.

2. A separable fastener comprising, in combination, two members, one of said members being provided with a slot, a tongue 55 pivotally engaged with the other member and adapted for insertion through said slot, said tongue when inserted through the slot of the second member being movable in a position to overlie both of the members, the pivoted end portion of the tongue and the opposite end portion thereof being raised, and a holding member slidably engaged with the first named member and 60 extending across both of the members when said members are in locking relation, said holding member extending between the raised portions of the tongue, said holding member passing over or from the tongue upon depression of the pivoted end portion 65 of the tongue with respect to the second plate, an end portion of the member with which the holding member is engaged being transversely enlarged to provide stop shoulders at the opposite sides of said member to 70 maintain the holding member against displacement.

3. A separable fastener comprising, in combination, two members, one of said members being provided with a slot, a tongue 75 pivotally engaged with the other member and adapted for insertion through said slot, said tongue when inserted through the slot of the second member being movable in a position to overlie both of the members, the 80 pivoted end portion of the tongue and the opposite end portion thereof being raised, and a holding member slidably engaged with the first named member and extending across both of the members when said members 85 are in locking relation, said holding member extending between the raised portions of the tongue, said holding member passing over or from the tongue upon depression of the pivoted end portion of the tongue with 90 respect to the second plate.

In testimony whereof I hereunto affix my signature.

JOSEPH H. REED.
